UNITED STATES PATENT OFFICE.

BENJAMIN L. CORNELIUS, OF HUTCHINSON, KANSAS.

GRAIN-CAR DOOR.

1,181,850.

Specification of Letters Patent.

Patented May 2, 1916.

Application filed September 9, 1913. Serial No. 738,784.

To all whom it may concern:

Be it known that I, BENJAMIN L. CORNELIUS, a citizen of the United States, residing at Hutchinson, in the county of Reno and State of Kansas, have invented certain new and useful Improvements in Grain-Car Doors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to grain doors and more particularly to a door for use on railway grain cars, the principal object of the invention being to provide a door of that general character wherein sections may be actuated independently of each other in order to vary the area of the door opening and thereby provide for better controlling the emptying of a car of loose grain. In accomplishing this and other objects of the invention, I have provided improved details of structure, the preferred form of which is illustrated in the accompanying drawings, wherein:

Figure I is a perspective view of a railway grain car equipped with a door containing my improvements. Fig. II is a perspective view of the door frame and portions of several of the door sections. Fig. III is a perspective view of the opposite portion of the door frame, part of the car being broken away to show the slides for carrying the door sections within the side of the car. Fig. IV is an enlarged vertical section of part of the door sill and the lower section of the door, showing the means for opening the lower section of a door when the car upon which the door is carried is loaded with loose grain. Fig. V is a vertical section on the line V—V, Fig. III, showing the rack and pinion mechanism illustrated in Fig. IV.

Referring more in detail to the parts:

1 designates a railway grain car of any ordinary construction, having a side door opening 2 provided with jambs 3 and a sill 4. One jamb 3 is provided with a vertical slot 6, which communicates with a space 7 between the inner and outer walls of the car, and a portion of the jamb at one side of the slot is provided with spaced trans-

verse grooves 8, the lower edges of which are in alinement with the upper edges of horizontal battens 9 that are fixed to the wall of the car within the chamber 7.

Slidably mounted on the sill 4 is a lower door section 11 comprising an enlarged base rail 12, that is adapted for travel on the sill 4 and through the lower chamber groove 8, and web 13, which is adapted for guided travel in the narrower portion of the slot 6. The lower door section may be of any desired height and is adapted for supporting an upper section 14 of like construction, except that the base rail 15 of the upper section is provided with a bottom groove, which fits over the upper edge of the web 13 of the lower door section, so that both sections are guided by the groove and slot connection when either of the sections is moved longitudinally relative to the other. There may be any suitable number of upper door sections 14, according to the width of the sections and the height to which the door opening 2 is to be closed.

Mounted on the jamb 3, at each door section position, is a staple 16, and mounted on each door section is a hasp 17 which is adapted for co-operation with the staple 16 or with a staple 18 on the chamber at the opposite side of the door opening, to lock the door sections in place; it being apparent that a padlock, or any suitable device (not shown) may be used to retain the door sections in open or closed positions after they have been moved to bring the hasps into proper relation with the staples.

It is apparent that when the car is empty, the door sections may be moved inwardly and outwardly by hand, but that when the car is loaded, the contents of car will tend to press the door sections outwardly and lock the same against the door jambs. In order to conveniently open the door against such pressure, and particularly to open the lower door sections so that loose grain may pour out at the bottom of the door, I provide the base rail 12, of the lower door section, with a rack 20 which is adapted to mesh with a pinion 21 that is mounted in a chamber 22 in the door sill and projects through a slot 23 into meshing engagement with the rack. The pinion 22 is carried on a shaft 24 comprising a cylindrical inner end 24' adapted for revoluble and sliding travel in the socket 25 in the door sill, a cylindrical outer end adapted for sliding and revoluble travel

in a bearing 26, that communicates with chamber 22 and with an outer socket 27, and a squared central portion 28, which is adapted for keyed relation with the squared aperture 29 in the pinion. The bearing 26 is square so that the squared portion 28 may be inserted or removed and is of such a size that the faces thereof contact with the shaft 24 to form a bearing. The outer crank handle 31 is pivotally connected to shaft 23, and may be turned on its mounting and nested within the socket 27 in the side of the car, when the pinion shaft is forced inwardly, and thereby avoid any projection beyond the plane of the side of the car.

In order to obviate stoppage of the lower door sections, on account of loose grain collecting in the chamber 6, I provide an opening 32 at the lower, inner corner of the opening, through which the grain may be removed in case any should be caught within the chamber.

In using the door, presuming all of the sections to be in closed position and the car loaded with loose grain, it is apparent that the door will completely close the opening, so that the grain is held securely within the car, and also that the car may be locked and sealed by means of the hasp and staple mechanism.

When the car is to be unloaded, the lower door section is unlocked, the crank handle removed from its socket and drawn outwardly, so that the squared portion of the shaft will key into the squared aperture in the pinion, and the shaft and pinion revolved to move the lower door section longitudinally into the chamber 6, the lower door section being guided by its contact with the upper door section, and with the battens within the chamber in the side of the car.

It is apparent that when the lower door

section is open, the loose grain will flow out beneath the upper sections, until the grain adjacent the door has been removed from the car, when the upper sections may be moved back by hand to afford access to the interior of the car.

It is apparent that after the lower door section has been opened by means of the rack and pinion mechanism, the handle shaft may be moved back until the pinion is carried on the handle portion of the shaft, so that it may revolve idly when the lower door section is closed by hand.

Having thus described my invention, what I claim as new therein and desire to secure by Letters Patent, is:—

The combination with a door frame, having a sill chamber and slot, and an outwardly opening socket and having a vertical slot, of a sectional door having a lower section, a base rail on said door section having a downwardly opening groove, a rack in said groove, a shaft revolvably mounted in said sill and adapted for longitudinal movement therein, and having a squared portion located in said sill chamber, a pinion meshing with said rack and mounted in said sill slot, and having a square aperture adapted for engagement by the squared portion of said shaft when at one limit of its transverse movement, and a handle hingedly mounted on said shaft and adapted to nest in the outwardly opening socket of said sill when said shaft is moved to the opposite limit of its transverse movement.

In testimony whereof I affix my signature in presence of two witnesses.

BENJAMIN L. CORNELIUS.
